BY HIS ATTORNEY.

AM. CARLSEN.

UNITED STATES PATENT OFFICE.

EMMET R. THOMAS, OF ST. PAUL, MINNESOTA.

BOAT AND TRUNK COMBINED.

1,345,416.

Specification of Letters Patent.

Patented July 6, 1920.

Application filed December 14, 1918. Serial No. 266,726.

To all whom it may concern:

Be it known that I, EMMET R. THOMAS, a citizen of the United States, residing at St. Paul, in the county of Ramsey and State of Minnesota, have invented a new and useful Boat and Trunk Combined, of which the following is a specification.

My invention relates to collapsible boats, and the object is to provide a combined boat and trunk, which may easily be converted into a trunk during transportation on an automobile or other vehicle, and formed into a boat with seats and supply compartments when arriving at a lake or other place where a boat is desired for fishing or other purposes.

In the accompanying drawing, Figure 1 is a top or plan view of the combined boat and trunk ready for service as a boat but with oars or paddles omitted, as they may be of any suitable form. Fig. 2 is a side elevation of Fig. 1. Fig. 3 is a bottom view of the boat shown in Figs. 1 and 2 with the left hand end section shown as detached and the right hand end section and the handles of the trunk omitted. Fig. 4 may be termed a front elevation of the device converted into a trunk. Fig. 5 is a detail edge view of one of the hooks 25 in Fig. 1. Fig. 6 is a section on the line 6—6 in Fig. 3 of the catches 14—16 only. Fig. 7 is a partly sectional side view of an oar and oar-lock suitable for this improved boat.

Referring to the drawing by reference numerals, the boat is tapered from the middle toward each of its ends, which are preferably truncated. The body of the boat is divided transversely into four sections, of which the middle sections, 8 and 9, are large enough to receive the end sections 10 and 11 respectively, as indicated by dotted lines within the middle sections in Fig. 1.

The two middle sections have their adjacent upper edges secured together by hinges 13, and the bottom edges therebelow by resilient hook-shaped catches 14 adapted to engage in eyes 15 of members 16 and thus hold the middle sections rigid in their unfolded or set-up position. The end sections 10 and 11 may be secured to the middle sections by different means. This I have to some extent shown by detachably securing the two sections by differently modified means. Thus I have shown the section 10 as having its corner irons 17 formed with broad hooks 18 arranged to be dropped into

grooves 19 of corner irons 20 fixed on the adjacent middle section, and between said corner irons the end section is provided with a double-ribbed vertical iron 21 arranged to slide down into a double-grooved iron 22 fixed on the section 8. In assembling said two sections said interlocking iron strips on the end section are pushed downward into the strips on the section 8 until they stop against terminals 23, (indicated in Fig. 4 by contracted end portions of the grooved irons) and thumb catches 24 are then turned as in the full line positions in Fig. 1, to keep the sections interlocked. And in the other end of the boat I have shown the section 11 as provided with two hooks 25 (see also Fig. 5), which support the section by resting upon the edge of the section 9, and also tend to hold the sections together by engaging partly downward into the section 9; a bolt 26 is then inserted through the adjacent sides of the two sections and a nut 27 on the bolt drawn tight; to make a watertight joint the bolt passes through a soft rubber washer 28 which fills between the two sections.

When the end sections are placed within the middle sections they are retained in that position by the catches 24 and 24^x. All the sections may have reinforcing corner irons 20, some of which may have interlocking edges as those marked 17 and 20.

To make the boat strong at the middle the hinges 13 are extended partly downward into the boat sections and secured thereto by screws 29. One of the sections is provided with two handles 30 for carrying the device as a boat or more so for carrying it as a trunk. One or both middle sections are also provided with sockets 31 adapted each to receive a stem like 32 of an oar-lock 33 (shown in Fig. 7). In said figure is also shown an oar composed of two sections, 34—35, pivoted together at 36 so that the oar may be either separated or folded at said joint and thus be made short enough to go inside the folded boat or trunk. During the use of such oars each joint of the oar sections is held rigid by pushing over it a snugly fitting sleeve 37.

To further describe the operation or handling of the device, it may be stated that when the device is folded up as in Fig. 4 a hook catch 38, or other suitable locking device secures together the edges of the middle sections opposite from their hinged edges.

When the device is thus folded up it may be carried at the rear end of an automobile or other light vehicle, by providing the end of the vehicle with two pegs or hooks and placing thereon the apertured lugs or ears 39 with which the section 9 is provided; or the trunk may be tied to the vehicle in any suitable way by a rope inserted in said ears, or in the handles 30; or if the vehicle is large enough for it the trunk may be placed upon it, for even so the device will occupy a space so small that it would not hold an unfolded boat or even a boat of the ordinary foldable type.

When the device is unfolded for service as a boat, the fixed boards 40 serve as seats for the occupants, and to said boards are secured by hinges 41 lids 42, resting on ledges 43 and having finger clearings 44. The spaces below said lids and seats serve as storage chambers for food-stuffs, clothes, fishing tackles and other equipment and articles, which are contained therein as in a trunk during the transportation and as in closed boat compartments during the use of the device as a boat.

What I claim is:

1. A collapsible boat partly tapered toward both ends and divided transversely into four hollow sections, the two middle sections being hinged together at the upper

edges and therebelow provided with means for holding said sections rigid at the hinges when the sections are unfolded; the end sections of the boat being detachably secured 35 to the hinged sections and of a size and shape permitting them to be placed one inside of each of the hinged sections, and means for holding the hinged sections folded with their upper sides together when so 40 desired.

2. The structure specified in claim 1, said end sections being each provided with a closure, part of which forms a seat and the rest of it a hinged lid. 45

3. The structure specified in claim 1, said hinged boat sections having sockets for holding oar locks when so desired.

4. The structure specified in claim 1, and means for holding the end sections down 50 into the hinged sections.

5. The structure specified in claim 1, and means on one of the hinged sections for suspending it from the end of an automobile or other vehicle when the boat is folded up 55 as a trunk.

6. The structure specified in claim 5, and handles on one of the middle sections of the boat for carrying the device in either folded or unfolded position. 60

In testimony whereof I affix my signature.
E. R. THOMAS.
